UNITED STATES PATENT OFFICE

2,656,805

SEWING MACHINE

Charles Reinhold, Geneva, Switzerland, assignor
to Gallaz and Co., Geneva, Switzerland, a corporation of Switzerland

Application November 15, 1950, Serial No. 195,862
In Switzerland November 23, 1949

7 Claims. (Cl. 112—258)

1

The present invention relates to a sewing machine having a vertical mounting plate shaped approximately like the machine, and set at a right angle with the normal direction of the seam, the function of said plate being to support the various mechanical parts in working order, without the help of an outer shell or housing.

Referring more particularly to the drawings wherein I have represented two embodiments of my invention, Fig. 1 is a view of the machine with its outer shell partly torn off showing the first embodiment; Fig. 2 shows a cross-section along II—II of Fig. 1; Fig. 3 is a cross-section on a larger scale; Fig. 4 is a view from beneath of a machine according to the second embodiment; the base being removed; Fig. 5 is a cross-section along V—V of Fig. 4.

The machine according to the first embodiment as shown in Figs. 1 to 3 comprises a base supporting a generally C-shaped mounting plate 3 by means of screws 2. This plate 3 is located in a plane set at right angles to the path travelled by the seam; said path being itself perpendicular to the plane of the drawing. The material is guided under the needle by the presser-foot 4. The contour of plate 3 corresponds approximately with the contour of the machine, this being true throughout its lower arm 3a, its upper arm 3b, its head 3c, and its vertical shank 3d.

The plate 3 bears all the mechanical parts with the exception of the electric motor, encased in a lateral bulge of the outer shell (see Fig. 2).

The bearings of the shafts of the wheel 6 driven by the motor, and of wheels 7 and 8 driven in turn by a belt 9, and of wheel 8 are all part of plate 3.

The crosses 10 mark the places of the other bearings of the loop taking device, of the driving levers, of the feed-dogs, and of the rod controlling the lateral displacement of the needle 11 as well as of the slack thread controlling lever 12 etc. It is to be understood that all possible constructions are not shown here, the character of the invention being that the machine shall be able to run with its outer case removed, all parts being supported by the mounting plate.

This makes for great simplicity in the assembling of the machine and in the timing and checking of its elements, which can all be easily reached for cleaning or repairing purposes.

The machinery is protected by a thin case formed by two shells 13 and 14.

These two shells are also supported by the plate 3 by means of cross-members 15, 16 (see Fig. 3), and a screw 17 and a nut 18.

2

The shells are also held to the plate at the points 19 of Fig. 1 by suitable fastening elements, as shown, and may be further attached, if desired, at other points where they do not interfere with the machinery.

Another departure from the conventional sewing-machine lies in the fact that the fly-wheel 8 is in a plane parallel to the plane of the drawing (plane of the mounting plate) instead of being perpendicular to it. This affords the use of an endless belt 9 for the drive of the wheels 6 and 7 lying in the same plane, instead of gears.

The shells, or at least one of them, have an aperture enabling the operator to hold the rim of the fly-wheel 8, for the purpose of starting or stopping the machine.

As seen in the cross-section of Fig. 3, the plate 3 is located off the symmetrical centre plane of the machine. It could of course be in the center but in locating it off center it is possible to fix on one of the faces the bulkier parts or even the whole machinery, without increasing the width of the case.

The plate 3 could also bear embossments in order to sustain some of the fixed or moving parts, and it could also have windows or ports as could be judged necessary or useful, it being understood that the drawing represents a simplification of the actual machine for convenience of illustration.

The bulge 5, protecting the motor could be part of the shell 14, and the shells 13 and 14 could be divided in several parts, for instance at the location of the head, in order to give access to the parts holding the needle or the slack thread controlling lever, or at the extremity of the lower arm in order to give access to the loop taking device and the bobbin case.

In the second embodiment the mounting plate 20 is not fixed to the base but instead it is supported by the two outer shells 24 and 25 as can be seen on Figs. 4 and 5. In this embodiment the plate 20 and the motor 21 are rigidly connected by cross-members 22 forming an assembly that will remain upright without the help of the plate or the base.

As in the first embodiment, the plate 20 is connected to the shells 24 and 25 by means of cross-members, here designated 23. But, contrary to the first embodiment, the connection to the base is not provided by the plate, but by the shells, which are provided with embossments 26, 27 and 28, and screws 29 (see Fig. 5).

The drawings show only some of the parts of the machinery, such as the pulley 30 which takes the place of the wheel 6 of Fig. 1, but it is to be

understood that the plate 20 supports all operative parts of the machinery in working order, including the motor.

To take the machine apart, it will be sufficient to unscrew the base and to remove the shells. A block of machinery will remain, made up of the mounting plate 20, the operating mechanism supported thereby, and the motor, the whole being in working order so as to afford an easy inspection of the operation of all parts and to permit convenient cleaning, repairs, and replacement of parts if necessary.

What I claim is:

1. In a sewing-machine, the combination of a base; a supporting standard of substantially C-shaped, plate formation rising from said base; a sewing needle and presser foot assembly operatively mounted across the open mouth of said supporting standard; drive mechanism mounted on said supporting standard, and comprising a series of drive wheels operatively interconnected by a drive belt, the wheels of said series being mounted for rotation on respective axes which are perpendicular to the plane of said supporting standard; and a substantially similarly C-shaped housing enclosing said supporting standard and the said drive mechanism mounted thereon.

2. In a sewing-machine, the combination of a base; a supporting standard of substantially C-shaped, plate formation secured to and rising from said base; a sewing needle and presser foot assembly operatively mounted across the open mouth of said supporting standard; drive mechanism mounted on said supporting standard, and comprising a series of drive wheels operatively interconnected by a drive belt, the wheels of said series being mounted for rotation on respective axes which are perpendicular to the plane of said supporting standard, one of the wheels of said series being a fly wheel mounted so as to project rearwardly of said supporting standard; and a substantially similarly C-shaped housing enclosing said supporting standard and the said drive mechanism mounted thereon, said housing having an aperture in its rear wall, through which a segment of the rim of said fly wheel projects to be available for manual manipulation.

3. The combination recited in claim 1, wherein the sewing needle and presser foot assembly are mounted in a plane transverse to the plane of the supporting standard, so as to sew a seam substantially perpendicularly to the plane of said supporting standard.

4. The combination recited in claim 2, wherein the sewing needle and presser foot assembly are mounted in a plane transverse to the plane of the supporting standard, so as to sew a seam substantially perpendicularly to the plane of said supporting standard.

5. The combination recited in claim 1, wherein in the supporting standard is a flat plate of uniform thickness; the housing is made up of substantially similarly shaped and recessed shells which meet in mutual opposition along a longitudinal plane disposed substantially centrally of the housing, said plate being disposed in a plane substantially parallel to but offset laterally from the said longitudinal meeting plane of the shells; and mutually spaced, removable and replaceable fastening devices securing said shells together and to said plate.

6. The combination recited in claim 5, wherein an electric motor is secured to a lower part of said plate and rests upon the said base at the side of said housing within which said plate is offset, said motor being enclosed by a shell which joins the said housing; and means securing the housing and said motor shell to the said base.

7. The combination recited in claim 1, wherein the supporting standard is secured to the base, and the housing is removably and replaceably secured to said standard.

CHARLES REINHOLD.
